RACKET FOR TABLE TENNIS

Byron C. Schmid, Washington, D. C.

Application June 19, 1950, Serial No. 10,624

Term of patent 14 years

(Cl. D34—5)

To all whom it may concern:

Be it known that I, Byron C. Schmid, a citizen of the United States, residing at Washington, D. C., have invented a new, original, and ornamental Design for Racket for Table Tennis, of which the following is a specification, reference being had to the accompanying drawing, forming part thereof.

The racket for a left handed player would be a mirror image of the racket shown in Figure 1.

I claim:

The ornamental design for a racket for table tennis, as shown and described.

BYRON C. SCHMID.
